UNITED STATES PATENT OFFICE

GEORGE W. RUSH, OF ALTOONA, PENNSYLVANIA.

DESIGN FOR A SHADE-BRACKET.

SPECIFICATION forming part of Design No. 30,099, dated January 31, 1899.

Application filed January 9, 1899. Serial No. 701,675. Term of patent 3½ years.

To all whom it may concern:

Be it known that I, GEORGE W. RUSH, a citizen of the United States, residing at Altoona, in the county of Blair and State of Pennsylvania, have invented and produced a new and original Design for Shade-Brackets, of which the following is a specification, reference being had to the accompanying drawing, forming part thereof.

The drawing shows a side view of a blank for a shade-bracket embodying my new design.

As shown in the drawing, the design consists of a major portion *a*, curvilinear in outline, expanding at its base into diverging arms *A* and *B*, and having laterally-projecting portions *b* and *c*. Extending substantially

parallel and in the same direction from the laterally-extending portions *b* and *c* are tapered extensions *d* and *e*, terminating in ²⁰ points, the extension *d* having a barb *f* on its outer edge.

The leading features of my design are the extensions *b*, *c*, *d*, and *e* and the barb *f*.

Having thus described my invention, what ²⁵ I claim as new, and desire to secure by Letters Patent, is—

The design for a shade-bracket, substantially as shown and described.

GEORGE W. RUSH.
